UNITED STATES PATENT OFFICE

MAX SAMUEL, OF ROSTOCK, GERMANY

RUBBER BRUSH

Application filed February 12, 1930, Serial No. 427,879, and in Germany April 18, 1928.

The present invention relates to an improved brush for the cleaning of leather and the like or for a massage, the body of which is made of soft vulcanized rubber and is provided on one or more sides with rubber bristles or teeth.

The action of such brushes improves with the sharpness of the bristle edges which come into action, for only these exercise a cleaning 10 scrubbing action. Round bristles or teeth with semi-cylindrical cross section have a very small cleaning power, but bristles and teeth of rectangular cross section with right angle edge angles have a better action.

According to the invention, a particularly good action is obtained by making the bristles or teeth in the form of three-edged prisms, so that the edges form acute angles. This 20 shape of rubber bristles is preferably used in such a manner that the longer bristles on one side are arranged in the form of vertical prisms, whilst the shorter bristles on the opposite side and the teeth along the edges are arranged in the form of horizontal prisms.

The invention is illustrated by way of example in the accompanying drawings, in which

Figure 1 shows a construction of the brush, in which the hollow shaped body is pushed 30 over a stem or handle, in side elevation, partly in section.

Figure 2 shows the brush in plan, and

Figure 3 is a view looking from the bottom.

Figure 4 shows another construction of the 35 brush without handle in side elevation, partly in section, and

Figure 5 is a view from the bottom, where 40 by only the left part of the brush is represented.

The handle 1 of the brush shown by the Figures 1-3 is pushed with its flat end into a corresponding hollow space of the brush body 2 which overlaps partly over the shoulders of the handle 1 at 3 in such a manner as to ensure a firm connection without the use of further means. The longer bristles 4 arranged on one side of the brush body 2, are of triangular cross section and on the whole 45 have the shape of a vertical three sided prism,

the single rows of prisms being arranged in alternate directions if desired.

The lateral row 5 is set with small teeth 6 in the form of horizontal three-edged members of prism-like shape.

On the side of the brush body opposite that of the longer bristles, are arranged bristles or teeth 7 which are pointed upwards and are of the shape of horizontal prisms.

The brush represented by the Figures 4 60 and 5 consists of a full shaped body 8 having on the one side long bristles 9 formed as vertical three-sided prisms the bristles 10 of the opposite side being equal shaped, but shorter. The lateral row is set with small prism-like 65 teeth 11 which are triangular in cross section, which give a sure holdfast for the hand.

I claim:

1. A brush consisting of an integral body of rubber and rubber teeth thereon in the 70 form of three-sided upright prisms.

2. A brush consisting of a substantially rectangular body of rubber and pairs of rows of rubber teeth in the form of upright prisms triangular in section, each pair of rows of 75 prisms having their bases alined and back to back.

3. A brush consisting of a body of rubber and rubber teeth formed on the one side of the body as long, on the other as short three- 80 sided upright prisms.

4. A brush consisting of a body of rubber and rubber teeth formed on the one side of the body as long, on the other side as short three-sided upright prisms, the edges of the 85 body having teeth of triangular cross-section with one side face attached to the body of the brush.

5. A brush consisting of a body with long upright teeth on one side of the body, the 90 other side and the edges having short teeth triangular in cross-section with one side face attached to the body of the brush.

In testimony whereof I affix my signature.

MAX SAMUEL. 95
